UNITED STATES PATENT OFFICE.

FRANK M. THOMSON, OF NEW YORK, N. Y., ASSIGNOR TO SHIELDS & BROWN, OF CHICAGO, ILLINOIS.

NON-CONDUCTING COVERING FOR PIPES.

SPECIFICATION forming part of Letters Patent No. 366,354, dated July 12, 1887.

Application filed November 23, 1886. Serial No. 219,565. (No model.)

To all whom it may concern:

Be it known that I, FRANK M. THOMSON, a citizen of the United States, residing at New York, in the county of New York and State 5 of New York, have invented certain new and useful Improvements in Non-Conducting Coverings for Pipes, Boilers, and other Surfaces, of which the following is a specification.

This invention relates to improvements in 10 non-conducting coverings for pipes, boilers, and other surfaces subject to undesirable extremes of temperature, and is composed of one or more layers of non-conducting material of the same kind, or alternated with or 15 constituting a filling or layers of a different kind, as the case may be, to attain the desired effect in a given application thereof.

Prior to my invention the materials used in the construction of non-conducting coverings, 20 whether in the form of one or more layers or as a filling for layers of other materials, have had an intrinsic and commercial value for other purposes than pipe-coverings, and besides, in many cases, are not good non-conduc- 25 tors at best, and, furthermore, are soon destroyed as such when exposed to the high degree of heat to which said coverings are necessarily frequently subjected.

The object of this invention is to utilize, 30 either in the form of one or more layers, or as a filling for non-conducting coverings, a hitherto waste product having little or no intrinsic or commercial value, and having a fiber naturally a non-conductor, the natural non- 35 conducting function of which fiber and the destruction of that function is not only prevented, but this function is promoted by the element necessary to its production.

To these ends my invention consists in a 40 non-conducting covering of sponge, preferably waste sponge, in one or more layers, or as a filling for and in combination with layers of other material, whether said other materials are good non-conductors or otherwise.

In carrying out my invention the covering 45 may be in tubular form, as shown in Figure 1, or in the form of a layer or layers, as shown in Fig. 2, and wholly of sponge, and one or both surfaces of either of these forms may, if 50 desired, be coated with any plastic material— such as cement, plaster-of-paris, &c.—for ex-

cluding air, or the sponge may have its outer surface covered with any of the usual fabrics, papers, or fibrous sheets commonly employed in making such coverings, whether said fabrics, papers, or fibrous sheets are plain, indented, or corrugated, or, as illustrated in the different forms in Figs. 3 and 4, respectively, cylindrical and in the form of flat layers. Said sponge may be employed as a filling be- 55 tween layers of a different material, whether of fabric, paper, or fibrous sheets, and either plain, indented, or corrugated.

In the drawings, A indicates the sponge, and B coverings of any of the other materials 60 in any of the forms, plain or otherwise, above referred to. When used alone, the sponge pieces, and necessarily in pieces, are held in the form of a layer or layers by any ordinary means, materials, or devices adapted for that 65 purpose—such, for example, as a cement or glue of some character, or by stitching with a thread substantially indestructible by heat, or which will hold the pieces of sponge until heat has rendered it a substantially compact layer 70 or caused the pieces to adhere together. When one or more layers of other materials are combined with the sponge, such layer and sponge may be secured together in any well-known manner, or the layer of sponge be placed upon 75 the article or device to be covered and the layer of other material placed and held on the sponge layer by any suitable means or manner to hold the pieces of sponge in position.

I have discovered by practical and satisfactory experiment that sponge is not only a 80 good non-conductor of heat in its natural state, but that its non-conducting functions are, if anything, improved after being subjected to heat sufficient to char it.

Sponge, which is not only clean but entirely 85 free of saline matter, requires considerable heat to char it, and may therefore be used as a covering for surfaces only moderately heated without being charred; but even when 90 so cleaned it does not burn to an ash, but chars at a higher degree of heat, and in this charred state is even a better non-conductor than in its natural condition. Usually, however, 95 sponge is cleansed to remove sand, gelatinous 100 and other matter by being thoroughly washed in sea-water, and as a result when the sponge

is dried contains saline matter. This saline matter in the sponge reduces the liability of the sponge to char, and hence sponge containing saline matter may be used as a covering for and on surfaces heated to such an extent that without such saline matter the sponge would be charred. The saline matter, however, which almost invariably exists in sponge, whether refuse or otherwise, has an important effect on sponge as a non-conductor, even when the heat of the surface to which the sponge covering is applied is sufficient to char the sponge, notwithstanding the presence of saline matter, for the saline matter materially promotes the quality, and hence the non-conducting effect, of the charred sponge, because it hardens and toughens the resultant char, and besides adds to it its own function of resisting destruction by heat, and reduces the porosity of the charred mass.

In practice I prefer and propose to use waste sponge, of which there is a large supply resulting from trimmings and imperfect pieces not trimmings, and unavoidably gathered while gathering sponge of a merchantable character; or I may use common coarse sponge without having to treat it to such an extent as to give it a merchantable value for present uses; but my invention includes the use of sponge, broadly, without regard to the degree of treatment it may have received to cleanse it, or whether or not it contains sa-

line matter, for after being once freed from gelatinous matter the after treatment of the sponge only modifies its non-conducting functions to an extent merely a question of degree; nor would it be any departure from my invention to combine with the sponge layer or filling other fibrous material, so long as the sponge predominates.

In conclusion, it may be added that by the employment of sponge, and particularly by what is known as "waste sponge," in coverings of the character herein referred to, a good non-conducting covering is not only produced, but one that is more durable and cheaper in proportion to the effects obtained than is now obtained.

Having described my invention, what I claim, and desire to secure by Letters Patent, is—

1. A non-conductor covering for pipes, boilers, and other surfaces, composed wholly or partly of sponge, substantially as described.
2. In a non-conductor covering for pipes, boilers, and other surfaces, the combination, with one or more layers of sponge, of one or more layers of other material or materials, substantially as described.

FRANK M. THOMSON.
